UNITED STATES PATENT OFFICE

THOMAS GRISWOLD, JR., OF MIDLAND, MICHIGAN, ASSIGNOR TO THE DOW CHEMICAL COMPANY, OF MIDLAND, MICHIGAN, A CORPORATION OF MICHIGAN

APPARATUS FOR CHEMICAL REACTIONS

Application filed January 27, 1927. Serial No. 163,929.

This invention relates to apparatus for chemical reactions where there is a mass of solid material and a gasiform substance, at elevated temperatures, and it is among the objects of the invention to provide efficient heating and control conditions. A further object is to provide for removing refuse from the site of reaction. Other objects and advantages will appear as the description proceeds.

To the accomplishment of the foregoing and related objects, the invention, then, consists of the features hereinafter fully described, and particularly pointed out in the claims, the following description and the annexed drawing setting forth in detail certain construction embodying the invention, the illustrative form shown however being but one of the various ways in which the principle of the invention may be applied.

In said annexed drawings:—

Fig. 1 is a vertical sectional view of one form of apparatus in accordance with the invention; and Fig. 2 is a sectional view taken on a plane at right angles to that shown in Fig. 1.

Referring more particularly to the drawings, the reference character 1 designates a reaction chamber adapted to contain heated solid material through which a gasiform substance is passed. Such reaction chamber is preferably of a separable or removable form, and may be tubular, either of circular or elliptical or other cross section. Preferably these reaction chambers may be made of ceramic material, although in some cases I contemplate metal. Below the reaction chamber, and, if desired, forming more or less of a support also therefor is a clean-out chamber 2. While this may be a masonry construction, preferably it will be of construction similar to the reaction chambers 1, as regards material. A door 3 affords access. A plurality of reaction chambers or retorts 1, each with its clean-out chamber, are massed in a common setting, a heating flue system being provided about the various units. A vaporizing vessel 4, preferably in the form of a tubular removable chamber, may be set on the clean-out base 2 similarly to the reac-

tion chambers. On the inner wall of the vaporizing vessel 4 is a spiral vaporizing gutter 5, the liquid to be vaporized being introduced thereto through a trapped inlet 6, supplied from a valve-controlled pipe 7. The heating flue also surrounds the vaporizing chambers, baffles being arranged to suitably divert the heating gaseous current about the reaction chambers 1, and the vaporizing vessels 4, and the clean-out chambers 2. As a preferred means of heating the assembly, there may be embodied in the setting a producer 9 for gas supply, such producer having a charging inlet 10 and clean-out 11, and delivering its gas through a duct 12 to mixing passages 13 where air, preferably preheated, is brought into relation with the gas for combustion. A system of transverse baffles 14 may be arranged to distribute the heat, as required. For preheating the inlet air, an exchanger or recuperator may be incorporated in the setting, and this may include an air intake conduit 15 in heat exchange relation with a discharge flue 16 for the flue gases on their way to the stack.

Surmounting the reaction chambers 1 are heads 17 having charging inlets 18; and off-takes 19 are arranged leading off to a condenser or absorber system, not shown.

The heads 17 may be of sufficiently large size to act as magazines for the material for the retorts.

Where solid material and a gasiform substance are subjected to high temperatures, whether the solid material be in the nature of a catalytic mass or as a direct reactant with a gasiform substance, the mass in the reaction chambers is heated by means of the flue system, and the gasiform substance is supplied from the vaporizers 4 through the base-chambers 2 so as to enter below and traverse the column of heated solid, and the gasiform products produced are taken off at the off-takes 19 to the condenser or absorber system. In the case of carbon disulphide manufacture, the reaction chambers 1 are filled with carbon, preferably in the form of charcoal, and are maintained at a temperature of red heat. Sulphur previously melted in a steam heated receptacle not shown, and forwarded

100

through pipe 7, is flowed into the vaporizers 4 where the liquid is vaporized, and the vapors thence pass to the retorts and pass upwardly therein to react with the hot charcoal, and the CS_2 is taken off at the offtake 19. From time to time refuse in the form of ash 5 from the carbonaceous material is raked out from the clean-out chambers 2, the doors being opened temporarily for this purpose. In this manner, since what ash is formed is at the base of the column of carbon, it may be kept from accumulating to hinder reaction. As the mass of carbon is used up at the bottom, the column settles down and is replenished by feeding in at the top 18 in accordance with the requirements.

By combining in a consolidated setting a plurality of reaction-chamber units, vaporizers and clean-out chambers and a gas producer or generator, heat is kept in the system, and uniformity and efficiency of operation is realized in high degree.

The baffling may be so arranged that by burning gas in the flues surrounding the reaction chambers 1, and returning the partly spent products of combustion around the vaporizing vessel 4, the former may be heated to a greater degree than the latter; and similarly by burning the gas in the flues about the vaporizing vessel and reversing the direction of the flow of the products of combustion, the vaporizing vessels may be heated more than the reaction chambers. Further, by burning gas in both sets of passages, with flow either in parallel or series, desired division of the total heat supplied may be secured as between the reaction chambers and the vaporizing vessels.

Other modes of applying the principle of the invention may be employed, change being made as regards the details disclosed, provided the means stated in any of the following claims, or the equivalent of such be employed.

I therefore particularly point out and distinctly claim as my invention:—

1. In apparatus of the character described, the combination of an externally heated vertically disposed tubular reaction chamber, an externally heated vertically disposed tubular vaporizing vessel, and an externally heated horizontally disposed clean-out chamber below said reaction chamber and vaporizing vessel, separate therefrom and communicating therewith.

2. In apparatus of the character described, the combination of a vertically disposed tubular reaction chamber, a vertically disposed tubular vaporizing vessel, heating means for externally heating said reaction chamber and vaporizing vessel, and an externally heated horizontally disposed clean-out chamber below said reaction chamber and vaporizing vessel, separate therefrom and communicating therewith, said reaction chamber and

vaporizing vessel being removable vertically without dismantling the heating means.

3. In apparatus of the character described, the combination of a plurality of externally heated reaction chambers, and a like plurality of externally heated vaporizing vessels, each said reaction chamber and vaporizing vessel resting in pairs upon horizontally disposed clean-out chambers and communicating therewith.

4. In apparatus of the character described, the combination of a plurality of externally heated reaction chambers, a like plurality of externally heated vaporizing vessels, each said reaction chamber and vaporizing vessel resting upon a horizontally disposed clean-out chamber and communicating therewith, and a supply conduit in common for feeding molten sulphur to said vaporizing vessels.

5. In apparatus of the character described, the combination of a combustion chamber arranged for the combustion of gases, a plurality of sets of vertically disposed tubular reaction chambers, vertical tubular vaporizing vessels, and horizontal clean-out chambers therebelow connected therewith, all set in said combustion chamber, and means to control the distribution of heat thereto, said means comprising baffles to lead furnace gases back and forth in a rising zig-zag path in heating relation to said chambers and vessels.

6. In apparatus of the character described, the combination of a plurality of sets of vertically disposed tubular reaction chambers, vertically disposed vaporizing vessels and horizontally disposed clean-out chambers therebelow, each said clean-out chamber supporting and communicating with a said reaction chamber and vaporizing vessel, said plurality of sets of chambers and vessels being positioned in a gas-fired furnace including therein baffles to lead heating gases back and forth in a rising zig-zag path in heating relation thereto.

7. In apparatus for making carbon disulphide, the combination with a vertically disposed ceramic tubular reaction chamber and a separate vertically disposed tubular sulphur vaporizing vessel, of a separate horizontally disposed ceramic clean-out chamber therebelow supporting said vertically disposed first-mentioned chamber and vessel and communicating therewith, means for supplying charcoal to said reaction chamber, and means for supplying sulphur to said vaporizing chamber.

8. In apparatus for making carbon disulphide, the combination of a vertically disposed reaction chamber, a vessel for supplying sulphur vapor to the reaction chamber and including an inclined gutter, a separate horizontally disposed clean-out chamber below and supporting said first-mentioned chamber and vessel and communicating

therewith, means for supplying charcoal to said reaction chamber, and means for supplying sulphur to said vaporizing chamber.

9. In apparatus for making carbon disul-

5 phide, the combination of a plurality of vertically disposed tubular reaction chambers and separate vertically disposed tubular sulphur vaporizing vessels, separate horizontally disposed clean-out chambers therebelow, each said clean-out chamber supporting a reaction chamber and a vaporizing vessel and communicating therewith, means for supplying sulphur to said vaporizing chambers, and means for heating the entire apparatus, said means including a producer of hot combustible gas, and a flue system for supplying the same about said chambers and vessels.

10. In apparatus for making carbon di-
20 sulphide, a plurality of sets of carbon disulphide producing units, each including a vertically disposed vessel to vaporize sulphur, and a vertically disposed tubular chamber to contain charcoal, said chamber and
25 vessel being above and communicating with a separate horizontally disposed clean-out chamber adapted to lead sulphur vapors from said vaporizing vessel to said reaction chamber and to accumulate and permit re-
30 moval of ash, heating means in the same setting, including a gas producer, a recuperator, and passageways to lead the heated gases back and forth in a rising zig-zag path in heating relation with said chambers and ves-
35 sels.

11. In apparatus of the character de-
scribed, a sulphur vaporizing chamber comprising a vertically disposed tubular vessel having upon its inner wall surface a spiral
40 gutter.

12. In apparatus for making carbon disulphide, the combination in a single setting, of a gas producer, recuperator, vertically disposed tubular ceramic reaction chamber, a vertically disposed tubular ceramic sulphur
45 vaporizing chamber having upon its inner wall surface a spiral gutter, and a horizontally disposed ceramic cleanout chamber supporting said reaction chamber and said sulphur-vaporizing chamber and communicat-
50 ing therewith.

13. In apparatus of the character de-
scribed, the combination of a plurality of tubular reaction chambers, a cleanout cham-
55 ber on which each reaction chamber is set, means for supplying vapors, said means in-
cluding a spiral gutter adapted to receive a liquid at its upper end and a tubular walled vessel carrying said gutter on its inner sur-
60 face and being mounted also on each said clean-out chamber, horizontally-baffled heating flues about said reaction chambers, vapor-
65 izing vessels and clean-out chambers, and means for supplying to said flues a hot com-
70 bustible gas, said means including a producer

in connection with said flue system and in the same setting.

Signed by me this 14th day of January, 1927.
